(57) **CLAIM**

The ornamental design for a control panel for medical equipment, as shown and described.

DESCRIPTION

FIG. 1 is a top left perspective view showing a control panel for medical equipment of our new design; FIG. 2 is a top right perspective view thereof; FIG. 3 is a left side elevation view thereof; FIG. 4 is a right side elevation view thereof; FIG. 5 is a front elevation view thereof; FIG. 6 is a back elevation view thereof; FIG. 7 is a top plan view thereof; and, FIG. 8 is a bottom plan view thereof.
The broken lines are included for the purpose of illustrating portions of the control panel for medical equipment that form no part of the claimed design.

1 Claim, 5 Drawing Sheets
